COMBINED COIN SAVINGS BANK AND PICTURE FRAME

Marion Constance Moran, Bradford, Pa.

Application April 21, 1950, Serial No. 9,409

Term of patent 14 years

(Cl. D34—11)

To all whom it may concern:

Be it known that I, Marion Constance Moran, a citizen of the United States, residing at Bradford, county of McKean, and State of Pennsylvania, have invented a new, original, and ornamental Design for a Combined Coin Savings Bank and Picture Frame, of which the following is a specification, reference being had to the accompanying drawing, forming part thereof.

In the drawing—

Fig. 1 is a front perspective view of a combined coin savings bank and picture frame, showing my new design;

Fig. 2 is a rear perspective view;

Fig. 3 is a top plan view;

Fig. 4 is a horizontal sectional view taken substantially along the line 4—4 of Fig. 1; and

Fig. 5 is a vertical sectional view taken substantially along the line 5—5 of Fig. 1.

The drawing is shaded to show transparency. The dotted line showing of a representative photograph is for illustrative purposes only.

I claim:

The ornamental design for a combined coin savings bank and picture frame, as shown and described.

MARION CONSTANCE MORAN.
